UNITED STATES PATENT OFFICE

WILLIAM E. WINE, OF TOLEDO, OHIO, AND GEORGE B. CHRISTIAN, OF WASHINGTON, DISTRICT OF COLUMBIA, ASSIGNEES TO WINE RAILWAY APPLIANCE COMPANY, OF TOLEDO, OHIO, A CORPORATION OF OHIO .

RAILWAY CAR

Application filed March 25, 1929. Serial No. 349,833.

Our invention relates to railway cars and more particularly to closures or doors employed in flat-bottom gondola cars and the like.

5 A principal object of the invention is to provide a closure for a lading discharge opening which is of rugged construction and may be easily operated.

A primary feature of the invention consists in integrally forming the closure with a plurality of diagonally extending reinforcing ribs or flanges.

Another feature of the invention resides in constructing the closure with reinforcing flanges which converge from adjacent the hinge edge thereof and intersect at a point adjacent the opposite edge thereof, the closure being also integrally formed with a member extending from the point of intersection of said reinforcing flanges to a point outwardly of the door to afford means for cooperating with a hook or the like for maintaining the closure in operative position.

25 A further feature of the invention consists in integrally providing the closure with marginal flanges and with a plurality of reinforcing members, the latter being disposed on the outer face of the closure and one of said reinforcing members having portions disposed on opposite sides of one of said marginal flanges, the outer end of said last-named reinforcing member being adapted to serve as means for cooperating 35 with a hook to maintain the closure in operative position.

A still further feature of the invention consists in integrally providing the closure with a socket on its outer face for accommodating a removable lever whereby the door may be moved to closed position.

40 A still further feature of the invention resides in constructing the closure in a plurality of independently movable sections which have portions respectively overlapping each other.

A still further feature of the invention consists in providing the car with means 45 for preventing the sections comprising the

closure from moving away from each other along their hinge axes.

Other and more specific features of the invention residing in advantageous forms and combinations of parts will hereinafter appear and be pointed out in the claims.

In the drawings illustrating a preferred embodiment of the invention:

Figure 1 is a fragmentary plan view of a flat-bottom gondola railway car.

Figure 2 is a side elevational view of that portion of the car construction illustrated in Figure 1.

Figure 3 is a sectional view taken on line 3—3, Figure 1.

Figure 4 is a sectional view taken on line 4—4, Figure 1.

Figure 5 is a perspective view of portions of the sections comprising the closure showing the manner in which they overlappingly engage each other.

Figure 6 is a sectional view taken on line 6—6, Figure 4.

Figure 7 is a sectional view taken on line 7—7, Figure 3.

Figure 8 is a fragmentary elevational view of the outer edge of one of the door sections, the door arm being shown in section.

Since the type of car chosen for illustrating the invention is of the well-known flat-bottom gondola type only portions of it have been shown and it is to be understood that the construction illustrated is duplicated on the opposite side of the car.

Referring more particularly to the drawings 1 indicates one of the side members of the car center sill and 2 the usual top cover plate thereof. The car floor 3 is preferably of sheet metal and is spaced above the center sill. At the opposite sides of the car the floor may be secured by rivets 4 to the lower inwardly projecting flanges 5 of the channel shaped side sills 6. The car sides may be conveniently formed of metal plates or sheets 7 which are overlappingly secured to the outer face of the side sill in any suitable manner (not shown).

The car floor may be formed with any number of openings 9, only one of which is 100

illustrated in the drawings, through which the lading of the car may be discharged and each of the openings is provided with a hingedly mounted closure 10. In order to permit the car to be quickly emptied of its contents it is the usual practice to make these discharge openings in cars of the type illustrated relatively large. In view of this fact correspondingly large closures must be employed for each of the openings which due to their weight require considerable effort on the part of trainmen to raise them to closed position. Especially is this true when cast doors are employed. In order to obviate this difficulty each of the closures is preferably made in two sections 11 and 12, the sections being so arranged and related that they in effect act as one door when in operative position but may be elevated or raised to closed position separately or independently. Each of the sections is preferably made of cast steel and is provided with downwardly projecting marginal flanges 13. The marginal flanges at the two side edges of each section and that one adjacent the hinged or inner edge terminate in inwardly projecting flanges 14, while the marginal flanges adjacent the outer or free edge of the door terminates in an outwardly projecting flange 8. Thus the side and inner edges of the sections are in effect channelled shaped while the outer edges thereof are Z-shaped.

Rigidly secured to the center sill are a plurality of properly positioned brackets 15 and 16 for hingedly connecting the closure to the car. Each of the brackets is formed with a base-plate 17 and with upwardly projecting side flanges 18, the base-plate being suitably apertured to receive rivets 19 employed for connecting the brackets to the center sill. Extending inwardly from each of the side flanges are hub portions 20 which are spaced apart a suitable distance to respectively receive the lugs 21 with which the closure sections are formed. Each of the brackets may be advantageously fashioned with a web 22 for respectively connecting the hub portions 20, the end flanges 18 and the base-plate 17. The lugs 21 are each formed with a hub portion 23 connected to the sections by a web 24 and side flanges 25, the outer side flanges of each of the hinge lugs constituting, in effect, continuations or prolongations of the marginal side flanges of the closure sections. The hub portions 20 of the brackets and 23 of the lugs are apertured to receive a pin 26 of any suitable construction for hingedly mounting the sections. As it is desirable to arrange the adjacent inner edges of the sections of each closure in close proximity the hub portions of the hinge bracket 16 are spaced a sufficient distance apart to receive the inner hinge lugs of adjacent sections.

To prevent the escape of fine lading between the adjoining edges of the sections a portion of one of them overlaps the adjacent portion of the other. In the drawings the main body portion of the door 11 projects outwardly in the form of a flange 27 beyond the inner side marginal flange thereof and the portion of the door 12 adjacent its inner edge is recessed as at 28 to receive the flange 27. In this manner the top surfaces of each of the door sections are disposed in substantially the same plane. Thus it will be seen that since the adjoining edges of the door are in overlapping relation and that the portions of the floor and side sill defining the lading discharge opening overlie adjacent portions of the closure the lading within the car is effectually prevented from accidentally escaping therefrom.

The outer face of each door section may be advantageously integrally formed with diagonal reinforcing flanges or ribs 29 which converge from adjacent its hinged edge and intersect at a point adjacent its opposite edge. It is preferred to arrange the inner side flange 25 of each of the hinge lugs 21 of the sections and the inner ends of the diagonal flanges so that they constitute continuations or prolongations of each other. To rigidify the diagonal flanges at their points of intersection they may be tied together by a horizontally disposed web 30.

Projecting outwardly beyond the free edge of each section from the point of intersection of its diagonal flanges is a member 31 which serves the dual function of a reinforcing member and an arm for cooperating with mechanism carried by the car to support the section in closed or operative positions. Thus it will be seen that each door section is reinforced by members arranged in substantially the form of a Y, the flanges 29 constituting the legs thereof and the member 31 the stem. Each of the members 31 comprises a web or flange 32 arranged substantially normal to the main body portion of the section and depends below the outer face of the door a greater distance than the diagonal and marginal flanges thereof. The lower edge of the member 31 is provided with a horizontal flange 33 which extends continuously from the diagonal flanges to the outer end of the member and the upper edge of that portion of the member between its outer end and the outer marginal flange of the section is likewise fashioned with a horizontal flange 34 disposed substantially in the plane of the main body portion of the section. The top and bottom flanges 33 and 34 of each member are preferably tied together by an end flange 35.

Pivottally mounted upon the side of the car are hooks 36 having a plurality of ledges

37 and 38 respectively adapted to cooperate with the top flange 34 of the member 31 of each section to support them in partially closed and fully closed positions. Overlying the outer face of each of the hooks 36 is a cover-plate 39 rigidly secured to the car by rivets 40, 41 and 42 which pass through the cover-plate, side sheets 7 and side sill 6. The rivet 41 forms a pivotal support for the hook and the one designated 42 forms a pivotal support for a locking cam 43 which is interposed between the side sill and cover-plate for cooperating with the hook to prevent the latter from accidentally moving to an unlocked position.

As considerable difficulty is often experienced in causing dump doors of railway cars to assume fully closed position due to distortion of the doors and their associated parts the cover-plate 39 of each hook may be formed with an outwardly projecting lug or flange 44, apertured as at 45 for receiving a removable door prying lever 46. In closing either one of the sections it may be raised to a position such that the ledge 37 of its associated hook may engage the flange 34 to maintain or support the section in a preliminary or partial position of closure. The lever 46 may then be inserted through the aperture 45 of the cover-plate into engagement with the under surface of the flange 34. The lever may then be caused to fulcrum on the cover-plate to force the door into a position such that the ledge 38 may engage the flange 34 to support the door in a final or fully closed position.

Each of the sections may be conveniently formed with an open ended socket 47 disposed inwardly of the outer edge thereof and preferably adjacent the point of intersection of the diagonal flanges. This socket is adapted to receive a lever 48 which upon being inserted therein and engaging the bottom edge of the outer marginal flange 45 may be employed to assist in lifting the sections to closed positions. This lever 48 may be employed to lift the door from an open position into a partially closed position and it may also be used in moving the door from a partially closed to a fully closed position should the operator find it unnecessary to make use of the mechanical advantage which would be obtained by the use of the lever 46 when cooperating with the apertured lug of the cover-plate. Thus it will be seen that the section may be moved to closed position by the use of the lever 48 alone or by the use of the lever 48 to raise the door to a partially closed position and then the use of the lever 46 to force the door from partially to fully closed position depending upon the exigencies of each particular case.

Rigidly secured to the underside of the bottom flange 5 of the side sill and the floor 65 3 by rivets 49 adjacent the outer side cor-

ners of each section are members 50, preferably in the form of angle irons for preventing movement of the sections away from each other along their hinge axes. The downwardly projecting flange 51 of each angle iron 50 is preferably flared outwardly as at 52 so as to insure that the sections will be brought into proper cooperative positions when they are being moved to closed position.

When it is desired to discharge the lading within the car the sections of each closure may be caused to move to open position either separately or simultaneously. In causing them to move separately the hook 80 supporting the section 12 will first be moved to an inoperative position permitting that section to gravitate to open position and then the hook supporting the section 11 may be moved to a similar position permitting 85 that section to also open. When it is desired to cause the sections to open simultaneously the supporting hook of section 11 is first moved to inoperative position but this will not enable that section to move to 90 open position since its flange 27 is in overlapping engagement with the top of the section 12 which is still maintained in close position by its associated hook. When this last-named hook is moved to an inoperative 95 position both of the sections will simultaneously move to open position. In the door closing operation it will of course be appreciated that it is always necessary to move the section 11 to closed position before the 100 section 12.

From the foregoing it will be evident that the closure although made in two sections functions when in closed position as a unitary door and that the sections are constructed and rigidified in a manner such that they will effectually withstand the severe service conditions to which they are subjected.

We claim:

1. In a railway car having a lading discharge opening, a hinged closure for said opening, said closure being integrally formed with reinforcing members which converge from adjacent the hinged edge of the closure and intersect at a point adjacent the opposite edge of the closure.

2. In a railway car having a lading discharge opening, a hinged closure for said opening, said closure being integrally formed with reinforcing flanges which converge from adjacent the hinged edge of the closure and intersect at a point adjacent the opposite edge thereof, said closure being also integrally formed with a member extending from adjacent the point of intersection of said reinforcing flanges to a point beyond an edge of the closure, and means for cooperating with said last-named mem- 130

ber for maintaining the closure in operative position.

3. In a railway car having a lading discharge opening, a closure for said opening, said closure being provided with lugs for hingedly connecting the closure to the car, and being also integrally provided with diagonal flanges extending from the hinge lugs and intersecting adjacent the edge of the closure opposite the hinged edge thereof.

4. In a railway car having a lading discharge opening, a closure for said opening, said closure being integrally formed with a plurality of diagonal reinforcing flanges and with a reinforcing member projecting outwardly beyond an edge of the closure, said reinforcing member having a flange adapted to cooperate with means to support the closure in operative position.

5. In a railway car having a lading discharge opening, a closure for said opening, said closure being integrally provided with diagonally arranged reinforcing flanges and with an angularly shaped member projecting outwardly beyond an edge of the closure, said member having a flange disposed substantially in the plane of the main body portion of the closure adapted to cooperate with means for supporting the door in closed position.

6. In a railway car having a lading discharge opening, a closure for said opening, said closure having outwardly projecting marginal flanges and integrally provided with a plurality of reinforcing members one of which is disposed on opposite sides of one of said marginal flanges and the outer end thereof being adapted to serve as means for cooperating with a hook to maintain the closure in operative position.

7. In a railway car having a lading discharge opening, a hingedly mounted closure for said opening, said closure having outwardly projecting marginal flanges and integral reinforcements arranged substantially in the form of a Y, the legs of the Y extending from the marginal flange at the hinged edge of the closure and intersecting adjacent the marginal flange at the opposite edge thereof.

8. In a railway car having a lading discharge opening, a hingedly mounted closure for said opening having outwardly projecting marginal flanges, said closure being integrally formed with diagonally arranged reinforcing flanges extending from the marginal flange at the hinge edge of the closure and intersecting inwardly of the marginal flange at the opposite edge thereof, said closure being also integrally formed with an angularly shaped reinforcing member extending from the point of intersection of the diagonal flanges to a point outwardly of the last-named marginal flange.

9. In a railway car having a lading dis-

charge opening, a closure for said opening, said closure being integrally formed with reinforcing members arranged in the form of a Y, and means rigid with the stem of the Y for cooperating with mechanism to support the closure in operative position.

10. In a railway car having a lading discharge opening, a hingedly mounted closure for said opening, said closure being integrally formed with a plurality of angularly disposed reinforcing members respectively intersecting at a point adjacent the free edge of the closure, one of said reinforcing members being adapted to cooperate with means for maintaining the closure in operative position.

11. In a railway car having a lading discharge opening, a hingedly mounted closure for said opening, said closure being integrally formed on its outer face with a socket for accommodating a removable lever whereby the closure may be moved to operative position.

12. In a railway car having a lading discharge opening, a hingedly mounted closure for said opening, said closure being integrally formed with a member projecting beyond an edge thereof adapted to cooperate with means for supporting the closure in operative position, said closure being also integrally formed with a socket adjacent the said member and inwardly of the free edge of the closure for receiving a removable lever whereby the latter may be moved to operative position.

13. In a railway car having a lading discharge opening, a closure for said opening, said closure involving a plurality of independently movable sections, each of the sections being integrally formed with a member projecting outwardly beyond an edge thereof, and a plurality of means for respectively cooperating with said outwardly projecting members for sustaining said sections in operative positions.

14. In a railway car having a lading discharge opening, a closure for said opening, said closure involving a plurality of independently movable sections, each of said sections being integrally formed with diagonally arranged reinforcing members and with an angularly shaped reinforcing member projecting beyond an edge thereof, and means for respectively cooperating with the outwardly projecting ends of said angularly shaped reinforcing members for sustaining the sections in operative positions.

15. A hinged door for a railway car integrally formed with diagonally arranged flanges intersecting inwardly of the free edge thereof, said door being also integrally formed with an angularly shaped member extending from the intersection of said diagonal flanges to a point outwardly of the said free edge of the door.

16. In a railway car having a lading discharge opening, a hinged closure for said opening, said closure comprising a plurality of independently movable sections, and means rigidly secured to the car body adjacent the outer side edges of the sections for preventing movement of said sections away from each other along their hinge axes.
- 5 17. In a railway car having a lading discharge opening, a closure for said opening provided with hinge lugs along one of its edges, rigidifying members for said closure arranged in substantially Y formation, the members constituting the legs of the Y respectively converging from adjacent the hinge lugs, and means rigid with the stem of the Y for cooperating with mechanism carried by the car to support the closure in operative position.
- 10 18. In a railway car having a lading discharge opening, a closure for said opening integrally formed with hinge lugs adjacent one of its edges, rigidifying members formed integrally with said closure and arranged in substantially Y formation, the members constituting the legs of the Y respectively converging from adjacent the hinge lugs and intersecting adjacent the opposite edge of the closure, and means rigid with the stem 25 of said Y for cooperating with mechanism carried by the car for supporting the closure in operative position.
- 20 19. In a railway car having a lading discharge opening, a closure for said opening provided with hinge lugs adjacent its inner corners, rigidifying members for said closure arranged in substantially Y formation, the members constituting the legs of the Y respectively converging from the hinge lugs 35 and intersecting adjacent the opposite edge of the closure, and means rigid with the stem of the Y for cooperating with mechanism carried by the car body to support the closure in operative position.
- 40 20. In a railway car having a lading discharge opening, a closure for the opening integrally formed with hinge lugs adjacent its inner corners, rigidifying members formed integrally with said closure and arranged in substantially Y formation, the members constituting the legs of the Y respectively converging from the said hinge lugs and intersecting adjacent the opposite edge of the closure, the member constituting 45 the stem of the Y projecting beyond the last-named edge of the closure for cooperating with mechanism to support the closure in operative position.

50 In testimony whereof we affix our signatures.
